(57) **CLAIM**

The ornamental design for a cabinet, as shown and described.

DESCRIPTION

FIG. 1 is a front, left, top perspective view of a cabinet, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 2;

FIG. 13 is an enlarged view of detail 13 in FIG. 2;

FIG. 14 is an enlarged view of detail 14 in FIG. 2;

FIG. 15 is an enlarged view of detail 15 in FIG. 2; and,

FIG. 16 is a front, left, top perspective view of the cabinet of FIG. 1, showing the cabinet in a stacked configuration environment.

The dashed broken lines shown in FIGS. 1-15 illustrate portions of the cabinet that form no part of the claimed design.

The dashed broken lines in FIG. 16 illustrate portions of the cabinet that form no part of the claimed design, or are directed to environment that form no part of the claimed design.

The dash-dot-dash broken lines shown in FIGS. 1-2 and 9-15 are for notating enlarged views and form no part of the claimed design.

1 Claim, 12 Drawing Sheets
